FIG. 1 is a perspective view of an outdoor quartz-halogen lamp lighting fixture showing our new design as viewed from the front of the fixture;

FIGURE 2 is a perspective view similar to FIGURE 1 but taken at a different angle;

FIGURE 3 is a front elevational view on a reduced scale of the fixture showing a portion of the lens and lens' frame broken away to depict the inner housing construction; and

FIGURE 4 is a rear perspective view on a reduced scale of the fixture.

The support element is fragmentarily shown in FIG. 3 for convenience of illustration.

We claim:

The ornamental design for an outdoor quartz-halogen lamp lighting fixture, substantially as shown and described.
